Application March 14, 1945, Serial No. 582,662

14 Claims. (Cl. 250—27)

1

This invention relates, in general, to pulse generators and is particularly directed to high-frequency pulse generators for developing a plurality of time-spaced pulses by the periodic charging and discharging of energy-storage devices. The term "high-frequency pulse generator" is here used to designate an arrangement for producing pulses which have a high repetition frequency, or a short time separation.

For some purposes it is desirable to develop large amounts of power for short time intervals and at relatively high repetition rates from low-voltage, low-power sources. Heretofore, there have been employed generators which utilize energy-storage devices that are periodically charged in a suitable manner from sources of the foregoing type, and are then discharged through gas-filled electron-discharge means to produce large values of power in an output circuit. Pulse-forming networks, or artificial transmission-line sections have been proposed for use as the energy-storage devices, since they are capable of delivering pulses of energy having substantially rectangular wave form and controllable durations which may be exceedingly short, for example, of the order of a microsecond. Hence, such high-power generators are suited to the development of periodic pulses having relatively high repetition frequencies.

Gas-filled electron-discharge means or tubes are particularly useful in arrangements of the foregoing character for discharging transmission-line sections, since these tubes, when conductive, have low anode-cathode impedances and low internal losses, and are able to conduct much larger currents than vacuum tubes of corresponding physical dimensions because of electron augmentation due to impact with gas molecules. Consequently, to develop a given amount of power, the operating potentials required for gas-filled tubes may be of considerably lower values, thus eliminating the need for high-voltage equipment, rigorous insulation-breakdown precautions, and shock safeguards.

However, in a pulse generator of the type in which output pulses are produced by periodically discharging an energy-storage device through a gas tube, the recharging of the energy-storage device, following each discharge thereof, must be carefully controlled. Specifically, the energy-storage device must be recharged by a suitable means which is effective to limit the current flow through the discharge tube during the deionization interval thereof to a value less than that required to sustain ionization. Various charging

2

circuits have been employed to control the recharging process. For example, linear-charging arrangements have been used. Such arrangements include a resistor of relatively high value for providing a charging interval that is long with respect to the deionization interval of the discharge tube, but this characteristic is objectionable when high-frequency operation is desired.

In other prior arrangements, faster charging is accomplished by replacing the resistor in the charging circuits with a series inductance which resonates with the capacitance of the energy-storage device. These other prior arrangements produce output pulses with a minimum time separation which approaches the deionization interval of the discharge tube. This limitation becomes significant where even a shorter time separation of the generated pulses is required.

It is an object of the present invention, therefore, to provide a high-frequency pulse generator which substantially avoids the aforementioned limitations of prior art arrangements.

It is another object of the invention to provide an improved high-frequency pulse generator including a plurality of energy-storage devices to be discharged through a common gas-filled device to generate a plurality of time-spaced pulses having a maximum separation which is less than the deionization interval of the gas-filled device.

It is a specific object of the invention to provide an improved high-frequency pulse generator including a plurality of energy-storage devices arranged consecutively to be discharged through a common gas-filled device to produce a plurality of output pulses having substantially equal amplitudes and pulse durations.

A high-frequency pulse generator for generating a plurality of time-spaced pulses in accordance with the present invention comprises a plurality of energy-storage devices and means for charging the energy-storage devices. The generator includes gas-filled electron-discharge means having a predetermined deionization characteristic and adapted to provide a single discharge path common to each of the plurality of energy-storage devices. The generator further includes means for successively completing discharge circuits through the single discharge path provided by the gas-filled means from each of the energy-storage devices in a predetermined sequence with a time separation between succeeding steps of the sequence which is less than the deionization interval of the gas-filled means, consecutively to discharge the plurality of energy-storage devices and produce a corresponding plu-

rality of output pulses having a predetermined time separation.

For a better understanding of the present invention, together with other and further objects thereof, reference is had to the following description taken in connection with the accompanying drawing, and its scope will be pointed out in the appended claims.

In the drawing, Fig. 1 is a schematic representation of a high-frequency pulse generator in accordance with the invention; and Fig. 2 includes a series of graphs utilized in explaining the operation of the Fig. 1 arrangement.

Referring now more particularly to Fig. 1, there is represented a high-frequency pulse generator for generating a plurality of time-spaced pulses. The illustrated arrangement, when keyed into operation by an applied control signal, produces a pair of time-spaced pulses having a desired duration and time separation. The generator includes a plurality, more specifically a pair, of energy-storage devices individually having the form of an artificial or simulated transmission-line section. One such line section 10 has high-potential terminals 11, 11' and a low-potential terminal 14. The line is formed of lumped circuit elements, including series-connected inductors 12, 12', 12'' and intermediate shunt condensers 13, 13', 13'' arranged to simulate a transmission line. A sufficient number of series and shunt elements is provided so that line section 10, in discharging, may deliver energy to a load circuit substantially continuously during a desired pulse interval. The pulse interval is determined by the product of the total inductance and total capacitance of the line section, which is selected in accordance with the desired pulse duration. A damping resistor 15 is bridged across inductor elements 12, 12'.

The other line section 16, which is also utilized as an energy-storage device in the generator, has a similar construction and includes a high-potential terminal 20 and a low-potential terminal 21. It is formed of lumped circuit elements shown as series-connected inductors 17, 17' and shunt-connected condensers 18, 18', 18''. A damping resistor 19 is bridged across inductors 17, 17'.

Where, as in the embodiment under consideration, it is desired to generate paired pulses having equal pulse durations, line sections 10 and 16 are so constructed that the product of the total inductance and total capacitance of each section is equal to a preselected constant value. While this product is the same for both sections, the condensers of line section 16 are selected so that the total capacitance of this section exceeds that of section 10. The purpose of this selection will be made clear hereinafter. In view of the described relationship of the inductance and capacitance of the line sections, the lines, if made of uniformly distributed parameters, have different characteristic impedances. However, in the preferred generator construction, the line sections are connected in cascade during a portion of the pulse-generating process and, therefore, it is preferable that each take the form of a tapered transmission line in order that this connection may be effected with substantial impedance matching to avoid reflection phenomena. To this end, the series-inductance and shunt-capacitance elements are selected so that each line section has the aforementioned inductance-capacitance product and an impedance characteristic which varies from a maximum at one end to a minimum at the opposite end. As illustrated, terminal 11 of

line section 10 is coupled to terminal 20 of line section 16, and the construction is such that the impedances at the adjacent ends of the sections are substantially matched.

5 A unidirectional conductive device, provided by a diode 25, connects terminal 21 of line section 16 with terminal 14 of line section 10, completing a parallel circuit arrangement. Means are coupled to this parallel arrangement for simultaneously charging each of the line sections to a particular level. This means consists of a source of unidirectional potential, indicated +B, coupled to the junction of terminals 11 and 20 by way of a duo-diode 26 and a saturable charging inductor 27. The charging circuit is completed by a ground connection 28. Inductor 27 represents the major inductive reactance of the described charging circuit and is selected of such value as to form, with the total capacitance of the two line sections 10 and 16, a series-resonant charging circuit. The circuit is resonant at a frequency approximately equal to one-half the maximum repetition frequency of the paired pulses.

The generator also includes a gas-filled tetrode 30, constituting gas-filled electron-discharge means having a predetermined deionization characteristic, for discharging each of line sections 10 and 16. The cathode of tube 30 is maintained at ground potential, and a bias-potential source 31 and grid resistor 32 apply an operating bias to the control electrode thereof for normally maintaining the tube in a nonconductive condition. A similar potential source 33 applies a negative potential to the shield electrode of the tube. The primary winding of a pulse transformer 35 couples the anode of tube 30 to high-potential terminal 11' of line section 10. Preferably, the load circuit of transformer 35 is so adjusted that, when tube 30 is rendered conductive, a matching impedance is coupled between high-potential terminal 11' and low-potential terminal 14 of the line section 10. By assuring substantial impedance matching at these terminals, maximum power transfer is obtainable from the generator to a load, represented by resistor 36 coupled to the secondary winding of pulse transformer 35.

There are also provided in the generator, selectively operable switching means for coupling the other line section 16 to tube 30. This means is a unidirectionally conductive device comprising a second gas-filled tube 40 of the tetrode type. The cathode of tube 40 is coupled to low-potential terminal 21 of line section 16, while its anode is conductively coupled to the cathode of the first gas tube 30, providing a loop circuit from line section 16 through line section 10 and tubes 30 and 40. Tube 40 is normally maintained in a nonconductive condition by means of a bias-potential source 41 coupled between its cathode and control electrode through the secondary winding of a pulse transformer 42 and a resistor 43. The shield electrode is biased to a suitable operating potential through a second source 44. The anode-cathode circuits of tubes 25 and 40, which couple the low-potential terminal 21 of line section 16 to ground, are conductive in opposite senses, one being utilized in the line-charging process and the other in the line-discharging process, as will be made clear hereinafter.

Finally, the generator has means for successively completing discharge paths through gas-filled tube 30 from each of the plurality of energy-storage devices of the generator in a predetermined time sequence with a time separation between succeeding steps of the sequence which

is less than the deionization interval of tube 30, consecutively to discharge each of the energy-storage devices to produce a corresponding plurality of output pulses having a predetermined time separation. This means includes a pair of terminals 50, 50 coupled to the input circuit of tube 30 through a condenser 51 for applying a control signal to initiate an electron discharge within this tube. The means under consideration for successively completing discharge paths for the energy-storage devices also includes a time-delay network 52 having input terminals 54, 54 coupled across terminals 50, 50. Delay network 52 is short-circuited at its remote terminals, as indicated at 53. The network may have any conventional construction and is selected to effect a predetermined total delay of an applied pulse, the delay being less than the deionization interval of tube 30, for any operating condition to be encountered. The primary winding of transformer 42 is coupled to input terminals 54, 54 of the delay network to apply a delayed control signal derived therefrom to the control electrode of the second gas-filled tube 40. A resistor 55 is coupled across this winding of transformer 42 to terminate network 52 in its characteristic impedance. The windings of transformer 42 are poled to obtain a polarity reversal of signals applied to its primary winding.

In considering the operation of the described generator, it will be assumed that both gas tubes 30 and 40 are in their normal nonconductive condition and that line sections 10 and 16 are acquiring a charge from source +B. The charging circuit for line section 16 is completed through diode 25 and the line sections are charged in parallel. When the charging process has been completed, the voltage established across the high- and low-potential terminals of each line section approaches twice the value of the charging source +B. The magnitude of the line potential results from the fact that in a series-resonant charging circuit, the potential developed across its inductive or capacitive reactance may readily approach twice the value of the charging source. This potential at the line terminals raises the potential level of the cathode elements of charging tube 26 a corresponding amount, biasing this tube to anode-current cutoff and interrupting the charging circuit. The generator is now in condition to respond to an applied keying or control signal applied to input terminals 50, 50 to supply to load impedance 36 a pair of time-spaced pulses.

The curves of Fig. 2 represent the response of the generator to such a keying signal. In this figure, curve A represents the keying signal, and curves B and C indicate the resulting control pulses applied to the control electrodes of tubes 30 and 40, respectively. Curves D and E designate, respectively, the potential relative to ground of the anode of tube 30 and the cathode of tube 40. Curve F represents the pulses generated in response to the discharging of line sections 10 and 16, and curve G shows these pulses as applied to load impedance 36.

At a time t_0 immediately preceding the application of the control or keying signal, both line sections are fully charged as stated above. The anode and cathode of tube 30 are directly coupled between high-potential terminal 11' and low-potential terminal 14 of line section 10, causing the anode potential to be at approximately twice the value of source +B. However, the anode and cathode electrodes of tube 40 are coupled across the high-potential terminal 20 and low-potential

terminal 21 of line section 16 through a series-circuit arrangement in which the line sections 10 and 16 are connected in phase opposition. Since the lines have identical charge conditions, the cathode of tube 40 is at zero potential with reference to ground. The described potential conditions are represented in curves D and E of Fig. 2.

At the time t_1 the keying signal of curve A, a pulse of positive polarity, is applied to terminals 50, 50. It is directly applied with the same polarity to the control electrode of tube 30 and to the input terminals of delay network 52, and is applied with reversed polarity through transformer 42 to the control electrode of tube 40, as shown by curves B and C. The control signal initiates an electron discharge in tube 30 but has no effect on tube 40 which remains in its non-conductive condition.

With tube 30 rendered conductive, a discharge path is completed for line section 10, extending from terminal 11' through the primary winding of transformer 35 and tube 30 to terminal 14. Transformer 35 terminates one end of line section 10 in a matching impedance, while the opposite end thereof is open-circuited since each of tubes 25, 26, and 40 is nonconductive. Thereupon, line section 10 completely discharges, generating a pulse P_1 which is applied directly to the load impedance 36. The duration T_d of pulse P_1 corresponds to the time interval $t_1 - t_2$ required completely to discharge line section 10. It is determined by the parameters of the line section, being approximately equal to twice the geometric mean of its total inductance and total capacitance.

The discharge of line section 10 effectively grounds terminals 11, 11' of line section 10 as well as the adjacent terminal 20 of line section 16. This removes the holding voltage established on the cathode elements of diode 26 when both line sections are fully charged, and causes the cathode potential of tube 40 to shift, becoming negative with respect to ground by approximately 2B or the potential of line section 16. With the holding voltage removed from diode 26, the charging circuit is completed and recharging of line section 10 is started. However, the saturable reactor 27 has a high initial inductance and so limits the current flow in the charging circuit that no appreciable charge is established on line section 10 during the deionization interval of tube 30. The deionization interval of tube 30 is the time required for the gas included therein to deionize following the occurrence of an electron discharge and the ionization of the gas incident thereto. The deionization interval is determined by the characteristics of the tube and the operating conditions of the generator. For the case under consideration, it is indicated $t_2 - t_5$. Consequently, at the time t_2 , the following conditions exist in the generator: the first pulse P_1 has been produced; the anode of tube 30 is at substantially ground potential; tube 40 is in its normal nonconductive state but its cathode has a negative potential relative to ground approximately equal to twice the value of source +B; and the deionization process of tube 30 has started.

After a preselected time interval represented $t_2 - t_3$, corresponding to the total time delay of network 52, a reflection of the keying signal of curve A appears at the network terminals 54, 54. The reflected signal results from the short-circuited termination 53 and is of negative polarity. It is applied directly to the control electrode of tube 30, but has no effect on this tube which con-

tinues to deionize. The reflected or delayed control signal is also applied to the control electrode of tube 40, but with positive polarity, receiving a polarity reversal in translation through transformer 42. The delayed control signal renders tube 40 conductive at time t_3 , which is delayed with reference to time t_2 such that the interval t_2-t_3 is less than the deionization interval of tube 30.

At time t_3 , line section 10 remains terminated in a matching impedance at terminal 11' since tube 30 is still ionized. The connection between terminals 11 and 20 of line sections 10 and 16, respectively, couples the adjacent ends of these sections with substantially matched impedances. Terminal 21, at the opposite end of line section 16, is effectively grounded through conductive tube 40, completing a discharge path for line section 16. This path extends from terminal 20 through line section 10, pulse transformer 35, tubes 30 and 40 in series, to terminal 21. The described discharge circuit establishes the same terminal conditions for line section 16 as those of line section 10 when tube 30 is initially rendered conductive to generate the first pulse P_1 . Namely, one end of line section 16 is terminated in a matched impedance by line section 10, while the opposite end thereof, including terminal 21, is open-circuited. Consequently, line section 16 discharges in a manner similar to the discharge of line section 10, producing at terminal 20 a second pulse P_2 of curve F. The duration of this pulse corresponds to the time interval t_3-t_4 required completely to discharge line section 16. Pulse P_2 is directly applied to terminal 11 of line section 10 and is translated therethrough, in conventional manner, to load impedance 36 by way of pulse transformer 35. Since the second pulse P_2 is generated in one line section and traverses the other in reaching the load 36, it is delayed with reference to the first pulse P_1 by a total time delay indicated T_s in curve G. The interval T_s includes the total time delay t_1-t_3 of delay network 52, plus the one-way delay of line section 10.

Shortly after time t_5 , when deionization has been completed in tube 30, charging reactor 27 becomes saturated and line sections 10 and 16 are rapidly recharged to approximately twice the value of source +B. Since the anode potential of tube 30 is determined by the charge condition of line section 10, the wave form of curve D, during the interval following the deionization period of tube 30, may represent the recharging process. At the end of this process, the potential conditions described in connection with the time t_5 are re-established and the generator is conditioned to respond to the next succeeding control signal to generate a further pair of time-spaced pulses P_1 and P_2 having a desired duration and time separation.

The generated pulses P_1 and P_2 have equal pulse durations T_d since each of line sections 10 and 16 has the same inductance-capacitance product. However, condensers 18, 18', 18'' of line section 16 have a greater total capacitance than condensers 12, 12', 12'' of line section 10, in order that the paired pulses P_1 and P_2 may also have substantially the same amplitudes. In this connection, it will be noted that the only impedances in the discharge path of line section 10 correspond to those of transformer 35 and discharge tube 30. On the other hand, the discharge path of line section 16 includes additional impedance elements, such as the second gas tube 40. By proportioning the capacitances of lines 10 and 16 with reference

to the impedances of their respective discharge paths, the output pulses P_1 and P_2 may have equal amplitudes.

Although the invention has been described in connection with an arrangement including but a pair of energy-storage devices individually to be discharged to generate a pair of time-spaced pulses, it will be understood that more energy-storage devices may be provided if desired. Each of the energy-storage devices is to be discharged through the common discharge tube 30. This may be effected by any suitable means which consecutively couples the energy-storage devices to the common discharge tube in a time sequence such that the succeeding steps of the sequence have a time separation which is less than the deionization interval of the discharge tube. Where this procedure is followed, discharge paths are consecutively completed through the common discharge device in a desired succession to discharge each of the devices and generate a corresponding plurality of time-spaced pulses having a preselected time separation. The time separation of the resulting pulses is determined largely by the preselected time sequence in accordance with which discharge circuits for the individual storage devices are completed through the common discharge tube.

It will be apparent that the line sections 10 and 16 need not be artificial lines constructed of lumped circuit parameters as described. Conventional distributed-constant line sections may be employed, if desired.

Pulse generators of the type described above may be utilized in communication systems for applying potential pulses to the anode of one or more tubes in the power oscillator circuit of a transmitter.

While applicant does not wish the invention to be limited to any specific circuit constants, the following circuit constants are given as illustrative of values of circuit elements which may be utilized in the circuit of Fig. 1.

45	Inductors 12 and 17	3.0 microhenries

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A high-frequency pulse generator for generating a plurality of time-spaced pulses comprising, a plurality of energy-storage devices, means for charging said energy-storage devices, gas-filled electron-discharge means having a predetermined deionization characteristic and adapted to provide a single discharge path common to each of said plurality of energy-storage devices, and means for successively completing discharge circuits through said single discharge path provided by said gas-filled means from each of said energy-storage devices in a predetermined sequence with a time separation between succeeding steps of said sequence less than the deionization interval of said gas-filled means consecutively to discharge said plurality of energy-storage devices to produce a corresponding plurality of output pulses having a predetermined time separation.

2. A high-frequency pulse generator for generating a plurality of time-spaced pulses comprising, a plurality of energy-storage devices, means for charging said energy-storage devices, gas-filled electron-discharge means having a predetermined deionization characteristic and adapted to provide a single discharge path common to each of said plurality of energy-storage devices, and means for successively completing discharge circuits through said single discharge path provided by said gas-filled means from each of said energy-storage devices in a predetermined sequence with a time separation between succeeding steps of said sequence less than the deionization interval of said gas-filled means consecutively to discharge said plurality of energy-storage devices to produce a corresponding plurality of time-spaced pulses having a predetermined polarity and occurring in a predetermined time sequence.

3. A high-frequency pulse generator for generating a plurality of time-spaced pulses comprising, a plurality of energy-storage devices, means for simultaneously charging said energy-storage devices, gas-filled electron-discharge means having a predetermined deionization characteristic and adapted to provide a single discharge path common to each of said plurality of energy-storage devices, and means for successively completing discharge circuits through said single discharge path provided by said gas-filled means from each of said energy-storage devices in a predetermined sequence with a time separation between succeeding steps of said sequence less than the deionization interval of said gas-filled means consecutively to discharge said plurality of energy-storage devices to produce a corresponding plurality of output pulses having a predetermined time separation.

4. A high-frequency pulse generator for generating a plurality of time-spaced pulses comprising, a plurality of energy-storage devices, means for simultaneously charging said energy-storage devices in parallel, gas-filled electron-discharge means having a predetermined deionization characteristic and adapted to provide a single discharge path common to each of said plurality of energy-storage devices, and means for successively completing discharge circuits through said single discharge path provided by said gas-filled means from each of said energy-storage devices in a predetermined sequence with a time separation between succeeding steps of said sequence less than the deionization interval of said gas-filled means consecutively to discharge said

5 10 15 20 25 30 35 40 45 50 55 60 65 70 75

plurality of energy-storage devices to produce a corresponding plurality of output pulses having a predetermined time separation.

5. A high-frequency pulse generator for generating a plurality of time-spaced pulses comprising, a plurality of energy-storage devices, means for charging said energy-storage devices, gas-filled electron discharge means having a predetermined deionization characteristic and adapted to provide a single discharge path common to each of said plurality of energy-storage devices but normally maintained in a nonconductive condition, and means for initiating an electron discharge in said gas-filled means and for successively completing discharge circuits through said single discharge path provided by said gas-filled means from each of said energy-storage devices in a predetermined sequence with a time separation between succeeding steps of said sequence less than the deionization interval of said gas-filled means consecutively to discharge said plurality of energy-storage devices to produce a corresponding plurality of output pulses having a predetermined time separation.

6. A high-frequency pulse generator for generating a plurality of time-spaced pulses comprising, a plurality of energy-storage devices, means for charging said energy-storage devices, gas-filled electron-discharge means having a predetermined deionization characteristic for discharging each of said plurality of energy-storage devices, and means including a time-delay network for successively completing discharge paths through said gas-filled means from each of said energy-storage devices in a predetermined sequence with a time separation between succeeding steps of said sequence less than the deionization interval of said gas-filled means consecutively to discharge said plurality of energy-storage devices to produce a corresponding plurality of output pulses having a predetermined time separation.

7. A high-frequency pulse generator for generating a pair of time-spaced pulses comprising, a pair of energy-storage devices, means for charging said energy-storage devices, gas-filled electron-discharge means having a predetermined deionization characteristic and adapted to provide a single discharge path common to each of said energy-storage devices, and means for successively completing discharge circuits through said single discharge path provided by said gas-filled means from each of said energy-storage devices with a time separation therebetween less than the deionization interval of said gas-filled means consecutively to discharge said pair of energy-storage devices to produce a pair of output pulses having a predetermined time separation.

8. A high-frequency pulse generator for generating a pair of time-spaced pulses comprising, a pair of energy-storage devices, means for charging said energy-storage devices, gas-filled electron-discharge means having a predetermined deionization characteristic for discharging each of said energy-storage devices but normally maintained in a nonconductive condition, means for coupling one of said energy-storage devices to said gas-filled means, switching means for coupling the other of said energy-storage devices to said gas-filled means, and means for initiating an electron discharge in said gas-filled means to complete a discharge path therethrough for said one energy-storage device and for operating said switching means with a predetermined time delay less than the deionization interval of said gas-filled means

to complete a discharge path for said other energy-storage device through said gas-filled means to discharge said energy-storage devices and produce a pair of output pulses having a predetermined time separation.

9. A high-frequency pulse generator for generating a pair of time-spaced pulses comprising, a pair of energy-storage devices, means for charging said energy-storage devices, a first gas-filled electron-discharge means having a predetermined deionization characteristic for discharging each of said energy-storage devices but normally maintained in a nonconductive condition, means for coupling one of said energy-storage devices to said first gas-filled means, a second gas-filled electron-discharge means for coupling the other of said energy-storage devices to said first gas-filled means but normally maintained in a nonconductive condition, and means for initiating an electron discharge in said first gas-filled means to complete a discharge path therethrough for said one energy-storage device and for initiating an electron discharge in said second gas-filled means with a predetermined time delay less than the deionization interval of said first gas-filled means to complete a discharge path for said other energy-storage device through said first gas-filled means to discharge said energy-storage devices and produce a pair of output pulses having a predetermined time separation.

10. A high-frequency pulse generator for generating a pair of time-spaced pulses comprising, a pair of energy-storage devices, means for charging said energy-storage devices, a first gas-filled electron-discharge means for discharging each of said energy-storage devices but normally maintained in a nonconductive condition, said first gas-filled means including a control electrode and having a predetermined deionization characteristic, a second gas-filled electron-discharge means including a control electrode for coupling the other of said energy-storage devices to said first gas-filled means but normally maintained in a nonconductive condition, and means for applying a control signal to said control electrode of said first gas-filled means to initiate an electron discharge therein to complete a discharge path therethrough for said one energy-storage device and for applying said control signal to said control electrode of said second gas-filled means with a predetermined time delay less than the deionization interval of said first gas-filled means to initiate an electron discharge in said second gas-filled means and complete a discharge path for said other energy-storage device through said gas-filled means to discharge said energy-storage devices and produce a pair of output pulses having a predetermined time separation.

11. A high-frequency pulse generator for generating a pair of time-spaced pulses comprising, a pair of energy-storage devices individually having a predetermined capacitance, means for charging said energy-storage devices, gas-filled electron-discharge means having a predetermined deionization characteristic for discharging each of said energy-storage devices but normally maintained in a nonconductive condition, means for coupling one of said energy-storage devices to said gas-filled means, switching means for coupling the other of said energy-storage devices to said gas-filled means, and means for initiating an electron discharge in said gas-filled means to complete a discharge path therethrough for said one energy-storage device and for operating said switching means with a predetermined time delay

less than the deionization interval of said gas-filled means to complete a discharge path for said other energy-storage device through said gas-filled means to discharge said energy-storage devices and produce a pair of output pulses having a predetermined time separation, said capacitances of said energy-storage devices being so proportioned with reference to the impedances of their respective discharge paths that said pair of output pulses have substantially equal amplitudes.

12. A high-frequency pulse generator for generating a pair of time-spaced pulses comprising, a pair of transmission lines individually having inductance and capacitance such that the product of inductance and capacitance of each line is equal to a preselected constant value, means for establishing a predetermined charge condition on each of said lines, gas-filled electron-discharge means having a predetermined deionization characteristic for discharging each of said lines but normally maintained in a nonconductive condition, means for coupling one of said lines to said gas-filled means, switching means for coupling the other of said lines to said gas-filled means, and means for initiating an electron discharge in said gas-filled means to complete a discharge path therethrough for said one line and for operating said switching means with a predetermined time delay less than the deionization interval of said gas-filled means to complete a discharge path for said other line through said gas-filled means to discharge said lines and produce a pair of output pulses having a predetermined time separation, said capacitances of said lines being so proportioned with reference to the impedances of their respective discharge paths that said pair of output pulses have substantially equal amplitudes and pulse durations.

13. A high-frequency pulse generator for generating a pair of time-spaced pulses comprising, a pair of transmission lines, means for charging said pair of lines, gas-filled electron-discharge means having a predetermined deionization characteristic for discharging each of said lines but normally maintained in a nonconductive condition, means for coupling one of said lines to said gas-filled means, means including a selectively operable switch for coupling the other of said lines to said gas-filled means through said one line, and means for initiating an electron discharge in said gas-filled means to complete a discharge path therethrough for said one line and for operating said switch with a predetermined time delay less than the deionization interval of said gas-filled means to complete a discharge path for said other line through said one line and said gas-filled means to discharge said pair of lines and produce a pair of output pulses having a predetermined time separation.

14. A high-frequency pulse generator for generating a pair of time-spaced pulses comprising, a pair of transmission lines, means including a first unidirectional conductive device for simultaneously charging said lines in parallel, gas-filled electron-discharge means having a predetermined deionization characteristic for discharging each of said lines but normally maintained in a nonconductive condition, means for coupling one of said lines to said gas-filled means, switching means including a second selectively operable and unidirectional conductive device for coupling said other line to said gas-filled means through said one line, and means for initiating an electron discharge in said gas-filled means to

complete a discharge path therethrough for said one line and for operating said switching means with a predetermined time delay less than the deionization interval of said gas-filled means to complete a discharge path for said other line through said one line and said gas-filled means to discharge said lines and produce a pair of output pulses having a predetermined time separation.
